INDEXING MECHANISM

Carl Herzog, Belleville, N. J.

Application June 5, 1943, Serial No. 489,829

18 Claims. (Cl. 74—120)

My invention relates to indexing mechanism.

An important object of the invention is to provide means which will effect an intermittent turning movement of an indexing element or table, and positively hold the same against turning movement during the working period.

A further object of the invention is to provide means of the above mentioned character which may be formed from racks and pinions, which are readily available.

A further object of the invention is to provide means whereby the extent of the turning movement of the indexing element or table may be varied, during the indexing period.

A further object of the invention is to provide means whereby a rotatable element which actuates the indexing mechanism is turned at a constant speed or a constant combination of speeds throughout a portion of the turning cycle during the working period and at an increased speed during the remainder of the turning cycle and during the indexing period.

A further object of the invention is to provide apparatus of the above mentioned character, which is automatic in operation, and positive and reliable in such operation.

Other objects and advantages of the invention will be apparent during the course of the following description.

In the accompanying drawings forming a part of this application and in which like numerals are employed to designate like parts throughout the same,

Figure 1 is a perspective view of the indexing mechanism embodying my invention.

Figure 2 is a perspective view of the means which intermittently turns the indexing table, showing the reciprocating carrier locked in the raised position, the locking rack held in the raised inactive position, and the indexing rack about to start upon its indexing movement.

Figure 3 is a similar view, showing the indexing rack at the end of its indexing movement, the reciprocating operating member moved down one half of its own stroke, the reciprocating carrier unlocked for downward movement, and the locking rack about to start upon its downward locking movement.

Figure 4 is a similar view, showing the reciprocating carrier locked at the end of its down stroke, the locking rack in the lowered locking position, the operating member in the lowermost position and the indexing rack at the end of its indexing movement and lowered.

Figure 5 is a similar view, showing the carrier

lowered and the operating member moved to one half of its up stroke to unlock the carrier, and the indexing rack shifted to the starting position while lowered,

5 Figure 6 is a horizontal section taken on line 6—6 of Figure 2,

Figure 7 is a perspective view, partly diagrammatic, of variable speed gearing, and

10 Figure 8 is a side elevation, partly diagrammatic, of hydraulic means to shift the carrier.

In the drawings, wherein for the purpose of illustration is shown a preferred embodiment of my invention, the numeral 10 designates a base, upon which is mounted a vertical housing 11.

15 This vertical housing receives a vertical rotatable shaft 12, upon which is mounted a horizontal rotatable indexing table 13 having a horizontal gear 14 beneath it. The gear 14 is rotatable with the table and serves to turn it. The table is 20 intermittently turned, during a portion of the turning cycle of the operating element and remains stationary during the remainder of the turning cycle. The table remains stationary during the work period. The speed of the turning 25 of the operating element must remain constant or have a constant combination of speeds during the work period but is increased during the indexing period.

Preferably formed integral with the housing 11 30 is a vertical frame 15, including an upper horizontal guide 16 and lower horizontal guides 17, as shown.

The numeral 18 designates a vertical reciprocating carrier or slide, having its vertical edges 35 slidably mounted within grooves 19 formed in the guide 16 and grooves 20 formed in the guides 17. This reciprocating carrier has a horizontal locking rack 21, preferably formed integral with its upper end. This locking rack is arranged to engage and disengage the gear 14.

The numeral 22 designates a vertical reciprocating operating member or slide, preferably in the form of a flat plate. The operating member or slide has its longitudinal edges slidably mounted 45 within vertical grooves 23, formed in the reciprocating carrier 18. The reciprocating operating member 22 is provided with a vertically inclined slot 24, provided at its ends with vertical extensions 25 and 26, extending downwardly and 50 upwardly, respectively, as shown.

The numeral 27 designates a horizontal reciprocating indexing rack, mounted for movement within a horizontal groove or guideway 28, formed upon the reciprocating carrier 18. The indexing rack 27 is arranged beneath and slid-

ably engages the locking rack 21 and the indexing rack has a longitudinal groove 29, receiving a depending tongue 30, carried by the bottom of the locking rack 21, as shown. It is thus seen that the indexing rack 27, the locking rack 21 and the reciprocating carrier 18 are all movable vertically as a unit, while the indexing rack 27 is movable horizontally with relation to the locking rack 21. The indexing rack 27 is movable vertically into and out of engagement with and from the gear 14 and also serves to turn this gear.

The guide 16 includes an outer horizontal arm 31, Figure 6, having a transverse horizontal opening 32 receiving a sliding bolt 33, which serves to lock the reciprocating carrier 18 in the elevated position. This bolt is movable into a notch 34 in the reciprocating carrier 18 and is sufficiently wide to project laterally beyond this notch. The inner end of the bolt 33 is spaced slightly from the reciprocating operating member 22 and is adapted to be engaged by a tapered lug 35, rigidly secured to the reciprocating operating member 22 and shifted downwardly to release the reciprocating carrier 18, when the operating member nears the half of its down stroke. The bolt 33 is moved inwardly to lock the reciprocating carrier 18 with the guide 16, when the operating member 22 nears the end of its up stroke, by a tapered finger 35', rigidly secured to an arm 36, in turn rigidly secured to the reciprocating operating member 22. The numeral 37 designates a companion sliding bolt mounted in a transverse opening 38, formed in the horizontal arm 31. This companion bolt is adapted to move into a notch 39, formed in the reciprocating carrier 18 and the bolt 37 projects laterally beyond the notch 39 and into the path of travel of a tapered lug 40, rigidly secured to the reciprocating operating member 22, and serving to withdraw the bolt 37 from the notch 39 when the operating member 22 nears the half of its up stroke. The bolt 37 is moved into the notch by a tapered finger 41, carried by an arm 42, rigidly secured to the reciprocating operating member 22, when such operating member nears the end of its down stroke.

The indexing rack 27 has a pin 43, rigidly secured thereto, carrying a roller 44, operating within the inclined slot 24. The extent of relative horizontal movement of the indexing rack depends upon the horizontal dimension of the inclined slot 24, and hence by varying the horizontal dimension of the slot 24, the throw of the indexing rack may be varied. Thus the throw of the indexing rack may be varied by changing the inclination of the slot 24. This may be accomplished by providing a number of operating members 22 having inclined slots 24 of different inclinations, and using a selected operating member 22. The inclined slot may be formed in a separate plate or insert detachably secured to the operating member, and different inserts having inclined slots of varying inclinations may be used with one operating member. It is thus seen that the means which effects the indexing movement of the indexing rack may be varied or adjusted to cause the indexing rack to move for different distances.

Pivottally connected with the reciprocating operating member 22, by means of a pin 45, is a pitman 46 pivotally connected at 47, with a disk 48.

Variable speed gearing is provided to drive the disk 48 and this gearing is mounted within a

gear casing or box 49. The gearing is preferably identical with that shown and described in my patent for Variable speed gearing, No. 2,338,514, dated January 4, 1944. This gearing includes a small gear 49' and an outer annular clutch element 50. The disk 48, gear 49' and clutch element 50 are connected to turn as a unit upon a horizontal shaft 51, by means of pins 52. A large gear 53 is rigidly mounted upon the shaft 51 and is connected with an inner clutch element 54, by means of pins 55, so that the gear 53 and clutch element 54 turn as a unit. The clutch element 54 extends into the annular clutch element 50 and rollers 56 are arranged between the clutch elements. An annular carrier 57 is mounted upon the outer clutch element 50 and an axially extending rotatable shaft 58 is mounted upon the carrier. This shaft has a small gear 59 rigidly secured to one end thereof, engaging the large gear 53 and a large gear 60 is rigidly mounted upon the opposite end of the shaft 58 and engages the small gear 49'. The carrier 57 is provided in its periphery with a tapered annular groove 61, receiving a brake element 62, carried by a pivoted lever 63, forced downwardly by a spring 64. The lever 63 carries a wheel 65, engaging a cam 66, preferably detachably mounted upon the disk 48. The cam 66 may extend for three-fourths of the circumference of the disk 48. The shaft 61 is driven in the direction of the arrow by a worm wheel 67, rigidly mounted thereon, receiving rotation from a worm 68, driven by a constant speed electric motor or the like.

While the wheel 65 is traveling upon the cam 66, the carrier 57 is free to turn with the clutch element 50, and all parts of the gearing turn as a unit, and the disk 48 is driven in the direction of the shaft 51 and at the constant speed of the shaft 51. This continues for three-fourths of the turning cycle of the shaft 51. During this portion of the turning cycle, the indexing table 13 is at rest, and hence the turning movement of the shaft 51 and the disk 48 must be constant, or have a constant combination of speeds as the working period of the indexing disk cannot be varied, for a selected working period. At the end of the three-fourths of the turning cycle, the roller 65 passes from the cam 66 and the brake element 62 engages the carrier 57 and holds it against turning movement. The shaft 51 now turns gear 53, turning gear 59 at an increased speed, and gear 59 turns gear 60, which turns gear 49' at an increased speed, and hence disk 48 is turned at an increased speed during the remainder of the turning cycle, which is the indexing period. It is thus apparent that the speed at which the indexing table is turned during the indexing period is increased, while the period at which the table is stationary, which is the working period, is not varied. Hence a great deal of time is saved by increasing the turning movement of the disk 48 and table 13, during the indexing period.

65 The operation of the indexing mechanism is as follows:

When the pin 47 has reached the uppermost position, Figure 2, and is about to start downwardly for the first substantially 90°, which is 70 the indexing portion of the turning cycle of the disk 48, the pitman 46 has raised the reciprocating carrier 18 to the uppermost position and the bolt 33 now locks the carrier to the stationary guide 16 in this uppermost position. The locking rack 21 is now above the gear 14 and free from

engagement therewith. As the disk 48 turns for its first upper 90°, Figure 3, the pin 47 travels downwardly carrying pitman 46 with it and the reciprocating operating member 22 is moved downwardly with relation to the then stationary carrier 18. The stationary carrier is locked against downward movement until the operating member 22 completes one half of its down stroke. At this time, while the pin 47 is traveling from the upper position in Figure 2 to the intermediate lower position of Figure 3, the indexing rack 27 is held by the carrier 18 against vertical movement with relation to the carrier and engages the gear 14. As the reciprocating member moves downwardly from the position in Figure 2 to the position in Figure 3, the roller 44 leaves the vertical extension 25 and enters the inclined slot 24 and this roller is shifted laterally to the right by this inclined slot, until the vertical extension 26 is reached. The roller 44 carries the indexing rack 27 with it and this rack engaging the gear 14, turns the gear for substantially 10° to 15° for effecting the indexing of the table 13. This indexing is effected rapidly as the variable speed gearing is now operating at high speed for the wheel 65 now disengages the cam 66. As the disk 48 turns downwardly through the upper 90°, from the position of Figure 2 to the position of Figure 3, and the operating member 22 reaches one half of its down stroke, the lug 35 moves the bolt 33 outwardly so that it releases the reciprocating carrier for downward vertical movement. The carrier 18 and operating member 22 are now both capable of moving downwardly as a unit. As the disk 48 turns downwardly for the second 90°, from the position of Figure 3 to the position of Figure 4, the carrier 18 and operating member 22 move down to the lowermost position. This downward movement of the carrier 18 lowers the locking rack 21 into locking engagement with the gear 14. When the carrier 18 moves down to the end of its down stroke, the notch 39 is brought into alignment with the bolt 37, and the finger 41 moves the bolt 37 into the notch 39 and locks the carrier 18 to the guide 16 against upward movement, Figure 4. The disk 48 now turns upwardly for the first 90° from the position in Figure 4 to the position in Figure 5, and the operating member moves upwardly with relation to the carrier 18. The indexing rack 27 is now arranged beneath and out of engagement with the gear 14. The upward movement of the operating member, Figures 4 and 5, causes the roller 44 within the inclined slot 24 to be shifted to the left whereby the indexing rack 27 is shifted to the left or starting position, Figure 5. The operating member 22 has now moved up to substantially one-half of its up stroke, and at this time the tapered lug 40 engages the bolt 37 and shifts it outwardly to release the carrier from the stationary guide 12. The carrier 18 and operating member 22 are now free to move upwardly as a unit, which occurs when the disk 48 turns for the second upper 90°, from the position shown in Figure 5 to the position shown in Figure 2. During the turning movement of the disk from the position of Figure 5 to the position of Figure 2, the carrier 18 and operating member 22 are both elevated and the locking rack 21 is moved above the gear 14 to disengage it while the indexing rack 27 is elevated to engage with the gear 14. When the carrier 18 reaches the end of its up stroke, notch 34 is in alignment with the bolt 33, and the finger 35 engages the bolt 33 and moves it into the notch 75

34, thereby locking the carrier 18 in the elevated position with the stationary guide 16. The parts thus assume the position shown in Figure 2 and the cycle of operation is repeated.

Attention is called to the fact that the locking rack 21 and indexing rack 27 are so arranged with respect to the gear 14 that the locking rack engages the teeth of the gear 14 before the indexing rack 27 disengages it. The indexing rack 27 has locking engagement with the gear 14 at the end of the indexing movement of the indexing rack to positively hold the gear 14 against overrunning movement. The operating member 22 reciprocates the carrier 18 and moves the indexing rack 27 with relation to the carrier. The operating member 22 also positively limits the movement of the indexing rack 27 at the end of its indexing movement. The carrier 18 moves axially of the gear 14.

While it is preferred to use variable speed gearing for reciprocating the operating member 22, yet the invention is not necessarily restricted to this arrangement, as hydraulic means may be employed for this purpose. This hydraulic means is shown in Figure 8, wherein a vertical cylinder 69 is provided, receiving a plunger 70, connected with the vertical rod 71, in turn connected with the reciprocating operating member 22. The numeral 72 designates valve mechanism to alternately supply liquid under pressure to one end of the cylinder 69 and to exhaust it from the opposite end. This valve mechanism is connected with pipes 75 and 76, which lead into a tank 77 holding a liquid, such as oil. The numeral 78 designates a pump connected with the pipe 75 and driven by a motor 79. The valve mechanism 72 includes a part 80 arranged to be engaged by cams 81 and 82. When the operating member 22 reaches the uppermost position, Figure 8, the cam 82 engages part 80 and the valve mechanism is actuated so that the liquid is supplied through pipe 75 and pipe 73 to the top of the cylinder 69, while fluid is exhausted from the lower end of the cylinder 69 through pipe 74 and pipe 76 back to the tank 77. When the piston 70 reaches the end of its down stroke, cam 81 trips part 80 and the liquid then passes through pipe 75 and pipe 74 into the bottom of the cylinder 69, while liquid is exhausted from the top of the cylinder 69 through pipe 73 and pipe 76 back to the tank 77. The piston 70 is then elevated and the cycle of operation is repeated.

It is to be understood that the forms of my invention herewith shown and described are to be taken as preferred examples of the same, and that various changes in the shape, size, and arrangement of parts may be resorted to without departing from the spirit of my invention or the scope of the subjoined claims.

Having thus described my invention, what I claim is:

1. In indexing mechanism, means to be indexed having gear teeth, a reciprocating carrier, a locking member mounted upon the carrier and movable into and out of engagement with and from the gear teeth, an indexing rack mounted upon the carrier to be moved thereby into and out of engagement with and from the gear teeth, said indexing rack having an indexing movement with relation to the carrier, and means to reciprocate the carrier and to effect the indexing movement of the indexing rack.
2. In indexing mechanism, means to be indexed having gear teeth, a reciprocating carrier, a locking member mounted upon the reciprocating car-

rier to be moved thereby into and out of engagement with and from the gear teeth, an indexing rack mounted upon the carrier to move therewith during its reciprocatory movement to engage and disengage the gear teeth, the indexing rack also having a reciprocatory movement with relation to the carrier which is transversely of the reciprocatory movement of the carrier, and means including a reciprocatory operating member mounted upon the carrier for movement with relation thereto to move the carrier and effect the indexing movement of the indexing rack.

3. In indexing mechanism, means to be indexed having gear teeth, a reciprocatory carrier, a locking member mounted upon the reciprocatory carrier to be moved thereby for engaging and disengaging the gear teeth, an indexing rack mounted upon the carrier to be reciprocated thereby for engaging and disengaging the gear teeth, said indexing rack also having an indexing movement transversely of the reciprocatory movement of the carrier, an operating member mounted upon the carrier and having a reciprocatory movement with relation to the carrier, said operating member having an inclined part, an element secured to the indexing rack and engaging said inclined part, means to reciprocate the operating member, and releasable means to hold the carrier against reciprocatory movement.

4. In indexing mechanism, means to be indexed having gear teeth, a reciprocatory carrier, a locking member mounted upon the reciprocatory carrier to be moved thereby for engaging and disengaging the gear teeth, an indexing rack mounted upon the carrier to be moved thereby for engaging and disengaging the gear teeth, said indexing rack also having an indexing movement with relation to the carrier, an operating member mounted upon the carrier and having a reciprocatory movement with relation to the carrier, said operating member having an inclined slot, an element secured to the indexing rack and arranged within the inclined slot, means operated by the operating member to lock the carrier against movement when the carrier and operating member are shifted to the ends of their strokes in one direction, means operated by the operating member to release the locking means, means operated by the operating member to lock the carrier against movement when the carrier and operating member move to the ends of their strokes in an opposite direction, means operated by the movement of the operating member with relation to the carrier in an opposite direction to its last named movement to release the last named locking means, and means to reciprocate the operating member.

5. In indexing mechanism, means to be indexed having gear teeth, a reciprocatory carrier, a locking member mounted upon the reciprocatory carrier to be moved thereby for engaging and disengaging the gear teeth, an indexing rack mounted upon the carrier to be moved thereby for engaging and disengaging the gear teeth, said indexing rack also having an indexing movement with relation to the carrier, an operating member mounted upon the carrier and having a reciprocatory movement with relation to the carrier, said operating member having an inclined device, an element secured to the indexing rack and engaging the inclined device, means to lock the carrier against movement when the carrier and operating member are shifted to the ends of their strokes in one direction, means to release the

locking means when the operating member is moved in an opposite direction for a part of its stroke with relation to the carrier, means to lock the carrier against movement when the carrier and operating member move to the ends of their strokes in an opposite direction, means to release the last named locking means when the operating member moves in an opposite direction to its last named movement with relation to the carrier, and means to reciprocate the operating member.

6. In indexing mechanism, means to be indexed having gear teeth, a reciprocatory carrier, stationary guide means for the carrier, a locking rack mounted upon the carrier, an indexing rack mounted upon the carrier and having an indexing movement with relation to the carrier, a reciprocatory operating member mounted upon the carrier and movable with relation to the carrier and having an inclined guide device, an element mounted upon the indexing rack and engaging the inclined guide device, a bolt mounted upon the stationary guide means, means mounted upon the operating member to move the bolt into locking engagement with the carrier when the operating member is moved in one direction with relation to the carrier, means mounted upon the operating member to shift the bolt out of locking engagement with the carrier when the operating member is moved in an opposite direction with relation to the carrier, a second bolt, means mounted upon the operating member to move the second named bolt into locking engagement with the carrier when the operating member is moved in an opposite direction to which it was moved to bring the first named bolt into locking engagement with the operating member, means mounted upon the operating member to move the second named bolt out of locking engagement with the carrier when the operating member is moved in a direction opposite to its last named movement, and means to reciprocate the operating member.

7. In indexing mechanism, indexing means, a reciprocatory carrier, a locking element mounted upon the carrier and movable thereby into and out of holding engagement with and from the indexing means, an indexing element mounted upon the carrier to be moved thereby into and out of engagement with and from the indexing means, said indexing element having an indexing movement with relation to the carrier while the indexing element has driving engagement with the indexing means, and means to reciprocate the carrier and to effect the indexing movement of the indexing element with relation to the carrier.

8. In indexing mechanism, indexing means, a movable carrier, a locking element mounted upon the carrier and moved by the carrier into engagement with the indexing means, an indexing element mounted upon the carrier and movable into engagement with the indexing means, said indexing element having an indexing movement with relation to the carrier while the indexing element has driving engagement with the indexing means, means to move the carrier, and means to effect the indexing movement of the indexing element with relation to the carrier.

9. In indexing mechanism, means to be indexed, a reciprocatory carrier, an operating member mounted upon the carrier and having a reciprocatory movement with relation to the carrier, said operating member having an inclined part, an element engaging the inclined part to be moved thereby, means operated by the operating member to lock the carrier against movement when the carrier and operating member move

together in one direction, means operated by the operating member when it is moved in an opposite direction to its first movement and with relation to the carrier to release the locking means, means operated by the operating member to lock the carrier against movement when the carrier and operating member move together in an opposite direction to their first movement, means operated by the operating member when it is moved in an opposite direction to the last movement of the carrier and member and with relation to the carrier to release the last named locking means, means to reciprocate the operating member, and a movable index member to engage the index means to be indexed and connected with said element to be moved by said element.

10. In indexing mechanism, indexing means, a reciprocatory carrier, a locking element mounted upon the reciprocatory carrier and movable thereby into and out of holding engagement with and from the indexing means, an indexing element mounted upon the reciprocatory carrier for movement with the carrier into and out of engagement with and from the indexing means, said indexing element having a reciprocatory movement with relation to the carrier which is transversely of the reciprocatory movement of the carrier, said indexing element having its indexing movement with relation to the carrier while the indexing element has driving engagement with the indexing means, and means to reciprocate the carrier and to effect the reciprocatory indexing movement of the indexing element with relation to the carrier.

11. In indexing mechanism, indexing means, a reciprocatory carrier, a locking element mounted upon the reciprocatory carrier and movable thereby into and out of holding engagement with and from the indexing means, an indexing element mounted upon the reciprocatory carrier for movement with the carrier into and out of engagement with and from the indexing means, said indexing element having a reciprocatory movement with relation to the carrier while the indexing element has driving engagement with the indexing means, means to reciprocate the carrier, and means to effect the reciprocatory indexing movement of the indexing element with relation to the carrier including an inclined part movable with relation to the indexing element and a part secured to the indexing element and engaging the inclined part.

12. The combination with a means to be advanced, of a reciprocatory carrier associated with the means, an advancing element mounted upon the carrier to be moved thereby into and out of engagement with the means, the advancing element having a reciprocatory movement with relation to the carrier while the advancing element is engaging the means, a reciprocatory operating member mounted upon the reciprocatory carrier, means to reciprocate the carrier and operating member as a unit and to reciprocate the operating member with relation to the carrier, and means operated by the movement of the operating member with relation to the carrier to move the advancing element.

13. In indexing mechanism, indexing means, a reciprocatory carrier, an indexing element mounted upon the reciprocatory carrier to be moved thereby into and out of engagement with the indexing means, the indexing element having a reciprocatory movement with relation to the carrier while the indexing element is engaging the indexing means, an operating member having

an inclined part, a part connected with the indexing element and engaging the inclined part, means to reciprocate the carrier and operating member as a unit and to reciprocate the operating member with relation to the carrier.

14. In indexing mechanism, means to be indexed including a movable member, said member having a stationary work period after the indexing period, a device to engage the member and upon its indexing movement to advance the member a step and having locking engagement with the member at the end of such step to positively hold the member against overrunning movement, means to intermittently move the device upon its indexing movement and positively limiting the movement of the device in the same direction when the end of the indexing movement of the device is reached, a rotary element connected with the intermittent means to drive the same, and variable speed mechanism connected with the rotary element to turn the rotary element at a constant speed during a portion of its cycle of turning movement and during the stationary work period of the movable member and to turn the rotary element at an increased total speed during the remainder of its cycle of turning movement and during the indexing period of the movable member.

15. In indexing mechanism, means to be indexed including a movable member, a device to advance the member a step upon the indexing movement of the device, said device having a positive connection with the member at the end of the step movement of the member to hold the member against overrunning movement, means to intermittently move the device upon its indexing movement and positively limiting the movement of the device in the same direction when the end of the indexing movement of the device is reached, a rotary element connected with the intermittent means to drive the same, and variable speed mechanism connected with the rotary element to turn the rotary element at a constant speed during the major portion of its cycle of turning movement and at an increased total speed during the minor remaining portion of its cycle of turning movement.

16. In indexing mechanism, means to be indexed having teeth, a reciprocatory carrier, a locking member mounted upon the carrier, an indexing member mounted upon the carrier to move with relation to the carrier, the locking member and indexing member being moved by the carrier into and out of engagement with the teeth, said members being so arranged that the locking member engages the teeth before the indexing member disengages the teeth, means including an operating member to reciprocate the carrier and to move the indexing member with relation to the carrier, the last named means positively limiting the movement of the indexing member at the end of its indexing movement, said indexing member having locking engagement with the teeth at the end of the indexing movement of the indexing member to positively hold the means to be indexed against overrunning movement, a rotary element turning about a fixed point, and means driven by the rotary element to reciprocate the operating member.

17. In indexing mechanism, a gear, a carrier mounted to reciprocate axially of the gear, an indexing rack mounted upon the carrier to reciprocate with relation thereto transversely of the movement of the carrier, a locking member mounted upon the carrier and arranged in close relation to the indexing rack, the carrier serving

to move the indexing rack and the locking member into and out of engagement with and from the gear and moving the locking member into engagement with the gear before the indexing rack disengages therewith, and means to reciprocate the carrier and to reciprocate the indexing rack with relation to the carrier.

18. In indexing mechanism, a gear, a reciprocating carrier mounted to move axially of the gear, an indexing rack mounted upon the carrier to reciprocate transversely of the carrier, the car-

rier moving the rack into and out of engagement with and from the gear, the indexing rack having locking engagement with the gear when the indexing rack is shifted to the end of its indexing movement, and means to reciprocate the carrier and to move the indexing rack with relation to the carrier and to positively limit the movement of the indexing rack when it reaches the end of its indexing movement.

10

CARL HERZOG.
